UNITED STATES PATENT OFFICE.

VALENTINE OPPL, OF SAN JOSE, CALIFORNIA.

EMBALMING PROCESS.

1,364,450.

Specification of Letters Patent.

Patented Jan. 4, 1921.

Application filed November 11, 1919. Serial No. 337,210.

To all whom it may concern:

Be it known that I, VALENTINE OPPL, a citizen of the United States, and resident of San Jose, Calif., in the county of Santa Clara, have invented certain new and useful Improvements in Embalming Processes, of which the following is a specification.

My invention relates to a means and method of embalming the human body after death, and it is the object of my invention to provide a method and means whereby the body may be preserved from putrefaction for an indefinite period of time.

In the drawing:

15 Fig. 1 is a front elevation of a vault as built for the purpose of applying my improved embalming process, part broken away.

20 Fig. 2 is a front elevation of the same with the door open and showing a casket in place therein.

Fig. 3 is an enlarged detail section on line 3—3 of Fig. 1.

25 Fig. 4 is an enlarged detail section on line 4—4 of Fig. 1.

Fig. 5 is a sectional view on line 5—5 of Fig. 1.

Fig. 6 is a sectional view on line 6—6 of Fig. 5.

30 Fig. 7 is a perspective view of the valved-casket.

Referring more particularly to the drawing, 1 is a concrete vault having positioned therein an air tight receptacle 2 secured by bolts 3 and built to withstand all unusual air pressures to which it may be subjected. Receptacle 2 is fitted with a door 4 hinged at 5 and supported when open by chain 6. Door 4 engages a rabbet 7 formed in receptacle 2 and fitted with a gasket 8 so that when closed and bolted as at 9 an air-tight receptacle is provided. In door 9 are provided a pair of valves as 10 and 11 for the purpose hereinafter described.

45 Within receptacle 2 are placed a pair of skids 12 whereby casket 13 is supported a distance from the bottom thereof and the air is allowed to circulate freely about the exterior of the said casket. In casket 13 are formed a plurality of valved openings 14 for the purpose hereinafter described.

Assuming that the body has been arranged

in casket 13 and the said casket positioned as shown and the door 4 securely bolted in a closed position, valves 14 in casket 13 being 55 left open. A vacuum pump is now applied to one of the valved openings as 11 and the air in receptacle 2 and casket 13 exhausted in so far as practical under the given conditions. When this has been effected valve 60 11 is closed and a compressed air pump is attached to valve 10 and air charged with a suitable antiseptic is forced into the receptacle 2 and casket 13 until a pressure exceeding two atmospheres has been attained 65 upon which the valve 10 is closed and sealed 65 and the pump removed.

A body subjected to the above treatment can be preserved indefinitely, especially if impregnated with an embalming fluid before 70 interment. However, neither the impregnation with an embalming fluid or the charging of the compressed air with an antiseptic is considered absolutely necessary as the air under high pressure will completely envelop 75 the body and effectively prevent the development of putrefactive micro-organisms. But in such cases especially where the body may be removed or exposed to the atmosphere at some future time it is considered best to 80 charge the compressed air with an antiseptic and in some cases, perhaps, to previously impregnate the body with a suitable embalming fluid. If the casket 13 containing the body is removed at some future time the valves 85 14 may be closed thereby preventing the entrance of air to the body and retaining there-in the antiseptically charged air.

It is understood that changes in form, material, proportions, method of operation and 90 details of construction may be made within the scope of the appended claim.

I claim:

The process of preserving a body from putrefaction which consists in placing the 95 same in a valved casket with the valves open, placing the casket in a vault embedded in insulating material, exhausting the air from said vault and casket, charging the vault and casket with compressed air impregnated 100 with an antiseptic, and finally permanently sealing the vault.

VALENTINE OPPL.
